UNITED STATES PATENT OFFICE.

GUSTAF A. HERMANSON, OF CHICAGO, ILLINOIS, ASSIGNOR TO JAMES MUNTON, OF MAYWOOD, ILLINOIS.

CAR-COUPING.

No. 830,713.

Specification of Letters Patent.

Patented Sept. 11, 1906.

Application filed December 18, 1905. Serial No. 292,209.

To all whom it may concern:

Be it known that I, GUSTAF A. HERMANSON, a citizen of the United States, residing in Chicago, in the county of Cook and State of Illinois, have invented a new and useful Improvement in Car-Couplers, of which the following is a specification.

My invention relates to improvements in car-couplers of the Master Car-Builders' type, having a forked draw-head, pivoted knuckle, and gravity-lock.

The object of my invention is to provide a car-coupler of a strong, simple, efficient, and durable construction, composed of few parts, in which the lock may be set in position for coupling and uncoupling, and in which when the cars are coupled together and the train is in motion the lock will be effectually prevented from "jumping" or "creeping," as it is called—that is to say, from accidentally moving upward, so as to permit the cars to become uncoupled, and thus endanger the safety of the train. Heretofore the lock has usually been prevented from creeping or jumping upward by making the lock in two pieces, one piece being the lock proper and the other being a lifting-piece having a sliding connection with the lower piece or lock proper; but this is objectionable because of the extra piece and additional expense of the lock and also because the sliding movement of the lifting-piece in respect to the lock makes an additional throw or extent of movement of the lifting-lever necessary, which is also objectionable in practical operation.

By my invention I provide a single-piece lock with a simple and efficient means for preventing its jumping or creeping, while at the same time the lock may be easily raised by the lifting-lever and the devices for preventing creeping disengaged.

My invention consists in the means I employ to accomplish this object or result—that is to say, it consists, in connection with the draw-head and knuckle of the coupler and gravity-lock, in providing the lock with a shoulder or device for preventing creeping of the lock at the upper end thereof, on its front side, which coöperates with an inwardly-projecting flange or shoulder on the draw-head to prevent the jumping or creeping of the lock, and in providing the lock near its lower end with a foot or projection on the rear side thereof, which engages the bottom

web or floor of the draw-head, upon which the lock is supported when it is in its lowermost or closed position, and this causes the upper end of the lock to normally tilt frontward, and thus hold the shoulders or devices on the lock and draw-head for preventing the creeping of the lock normally in engagement with each other, while at the same time the lock when it is raised by the lifting -lever is free to tilt forward at its upper end, and thus disengage the shoulders or devices on the lock and draw-head, which normally prevent the upward movement of the lock or its creeping or jumping.

It further consists, in connection with these parts, in providing the lock with an inclined cap or flange at its upper end, which engages an inclined face or seat on the draw-head and also aids in holding the shoulders or devices on the lock and draw-head for preventing of creeping in normal engagement with each other.

My invention also consists in the novel construction of parts and devices and in the novel combination of parts and devices herein shown and described.

In the accompanying drawings, forming a part of this specification, Figure 1 is a central vertical longitudinal section of a car-coupler embodying my invention. Fig. 2 is a vertical section on line 2 2 of Fig. 1. Fig. 3 is a horizontal section on line 3 3 of Fig. 1, and Fig. 4 is a detail elevation of the lock.

In the drawings, A represents the draw-head, having the customary pivot-arm a and guard-arm a'.

B is the knuckle, having the customary front arm or nose b and rear arm or tail b', C the pivot-pin, and D the lock.

The lock D has a lock-set leg d, having a lock-set ledge or shoulder d' to engage the bottom web or floor a² of the draw-head, and thus hold the lock in position for uncoupling. The lock D also has a lock-set shoulder or ledge d², adapted to engage the rear arm or tail of the knuckle and set or hold the lock in position for coupling when the knuckle is open. The lock D is further provided at or near its upper end and on its front side with a shoulder or device d³, which engages a corresponding inwardly-projecting flange or shoulder a³ on the draw-head adjacent to the opening therein for the lock. The interengaging shoulders d³ a³ prevent the lock when it is in

its closed or lowermost position from jumping or creeping or from being moved upward at all except by first giving the lock a rearward tilting movement at its upper end, as is 5 done by the arm f of the lifting-lever F when the lifting-lever is operated to raise the lock. The lock is further provided at its upper end with a cap or flange d^4 , which overlaps the opening in the draw-head and closes the same. 10 This cap or flange d^4 of the lock is upwardly and backwardly inclined, preferably about as illustrated in the drawing in Fig. 1, and the corresponding face a^4 of the draw-head surrounding the lock-opening therein is also 15 preferably similarly inclined, so that the front edge or flange d^5 of the lock will overhang and engage or come over the flange a^5 of the lock. The inclined cap of the lock, in connection with the coöperating inclined upper face on the 20 draw-head, thus tends to cause the upper end of the lock to slide or tilt forward and maintain the shoulders d^5 a^5 in engagement with each other when the lock is in its lowermost position. This action or tendency is further 25 occasioned or aided by the foot or projection d^6 on the rear face of the lock, near the lower end thereof, which engages and rests upon the bottom web or floor a^2 of the draw-head. This foot or projection d^6 at the rear side of the 30 lock, near the lower end thereof, thus gives the lock a pivotal support near its lower end well to one side of its center of gravity, and thus tends to tilt the upper end of the lock forward and maintain the lock-creeping-prevention shoulders d^3 a^3 in engagement with each other. The foot or projection d^6 extends 35 somewhat below the lock-set shoulder d^2 of the lock, so that this lock-set shoulder d^2 does not rest upon the bottom web or floor a^2 of the draw-head, as has heretofore been customary.

I claim—

1. In a car-coupler, the combination with the draw-head and pivoted knuckle, of a single-piece lock extending through the draw-head from top to bottom and provided with a shoulder on its front side near its upper end to prevent jumping or creeping of the lock, said draw-head having an inwardly-projecting flange or shoulder coöperating with said shoulder on the upper end of the lock and said lock being adapted to tilt backward at its upper end when raised by the lifting-lever and thus disengage said shoulder at its upper 55 end from the shoulder on the draw-head, substantially as specified.

2. In a car-coupler, the combination with the draw-head and pivoted knuckle, of a single-piece lock extending through the draw-head from top to bottom and provided with a shoulder on its side near its upper end to prevent jumping or creeping of the lock, said draw-head having an inwardly-projecting flange or shoulder coöperating with said shoulder on the upper end of the lock and

said lock being adapted to tilt backward at its upper end when raised by the lifting-lever and thus disengage said shoulder at its upper end from the shoulder on the draw-head, said lock being also provided near its lower end on 70 its rear side with a foot or projection to support the lock on the bottom web or floor of the draw-head to one side of its center and thus cause the upper end of the lock to normally tilt forward when the lock is in its lowermost position and thereby maintain said shoulder on the lock in engagement with said coöperating shoulder on the draw-head, substantially as specified.

3. In a car-coupler, the combination with 80 the draw-head and pivoted knuckle, of a lock provided with a shoulder on its front side near its upper end to prevent creeping or jumping of the lock, said draw-head having an inwardly-projecting flange or shoulder coöperating with said shoulder on the upper end of the lock, and said lock being adapted to tilt 85 backward at its upper end when raised by the lifting-lever and thus disengage said shoulder at its upper end from the shoulder on the 90 draw-head, said lock being also provided near its lower end on its rear side with a foot or projection to support the lock on the bottom web or floor of the draw-head to one side of its center and thus cause the upper end of the 95 lock to normally tilt forward when the lock is in its lowermost position and thereby maintain said shoulder on the lock in engagement with said coöperating shoulder on the draw-head, said lock having at its upper end an inclined cap or flange, and said draw-head having an inclined upper face surrounding the lock-opening therein, substantially as specified.

4. In a car-coupler, the combination with 105 the draw-head and pivoted knuckle, of a single-piece lock extending through the draw-head from top to bottom and provided with a shoulder on its front side near its upper end to prevent jumping or creeping of the 110 lock, said draw-head having an inwardly-projecting flange or shoulder coöperating with said shoulder on the upper end of the lock and said lock being adapted to tilt backward at its upper end when raised by the lifting-lever and thus disengage said shoulder at 115 its upper end from the shoulder on the draw-head, said lock having at its upper end an inclined cap or flange and said draw-head having an inclined upper face surrounding the lock-opening therein, substantially as specified.

5. In a car-coupler, the combination with the draw-head, of a knuckle and a single-piece lock extending through the draw-head 125 from top to bottom and provided with a lock-set leg at its lower end having a lock-set shoulder, and furnished on its front side near its upper end with a shoulder to prevent creeping or jumping of the lock, said draw- 130

- head having a projecting flange or shoulder | when raised by the lifting-lever and thus dis-
5 coöperating with said shoulder near the up-
per end of said lock and said lock being
adapted to tilt backward at its upper end
when raised by the lifting-lever and thus dis-
engage said shoulder at its upper end from
the shoulder on the draw-head, substantially
as specified.
6. In a car-coupler, the combination with
10 the draw-head, of a knuckle and a single-
piece lock extending through the draw-head
from top to bottom and provided with a lock-
set leg at its lower end having a lock-set
shoulder, and furnished on its front side near
15 its upper end with a shoulder to prevent
creeping or jumping of the lock, said draw-
head having a projecting flange or shoulder
coöperating with said shoulder near the up-
per end of said lock and said lock being
20 adapted to tilt backward at its upper end
when raised by the lifting-lever and thus dis-
engage said shoulder at its upper end from
the shoulder on the draw-head, said lock
having also a lock-set shoulder adapted to
25 engage the rear arm or tail of the knuckle
when the knuckle is open, substantially as
specified.
7. In a car-coupler, the combination with
30 the draw-head and pivoted knuckle, of a
lock provided with a shoulder on its front
side near its upper end to prevent jumping
or creeping of the lock, said draw-head hav-
ing an inwardly-projecting flange or shoul-
35 der coöperating with said shoulder on the up-
per end of the lock and said lock being adapt-
ed to tilt backward at its upper end when
raised by the lifting-lever and thus disen-
gaged said shoulder at its upper end from the
40 shoulder on the draw-head, said lock having
at its upper end an inclined cap or flange and
said draw-head having an inclined upper
face surrounding the lock-opening therein,
said lock being also provided near its lower
45 end on its rear side with a foot or projection
to support the lock on the bottom web or
floor of the draw-head to one side of its center
and thus cause the upper end of the lock to
normally tilt forward when the lock is in
50 its lowermost position and thereby maintain
said shoulder on the lock near the upper end
thereof in engagement with said coöperating
shoulder on the draw-head, substantially as
specified.
8. In a car-coupler, the combination with
55 the draw-head, of a knuckle and a single-
piece lock extending through the draw-head
from top to bottom and provided with a lock-
set leg at its lower end having a lock-set
shoulder, and furnished on its front side near
60 its upper end with a shoulder to prevent
creeping or jumping of the lock, said draw-
head having a projecting flange or shoulder
coöperating with said shoulder near the up-
per end of said lock and said lock being
65 adapted to tilt backward at its upper end
when raised by the lifting-lever and thus dis-
engage said shoulder at its upper end from
the shoulder on the draw-head, substantially
as specified.
9. In a car-coupler, the combination with
70 the draw-head, of a pivoted knuckle and a single-
piece lock extending through the draw-head
from top to bottom and provided with a lock-
set shoulder to engage the draw-head and set
or support the lock in position for uncoupling,
75 and a further lock-set shoulder to set or sup-
port the lock on the rear arm or tail of the
knuckle in position for coupling, said lock be-
ing also provided on its front side near its
upper end with a shoulder to prevent creep-
ing of the lock, said draw-head being provided
with a flange or shoulder to engage said shoul-
80 der on the lock near the upper end thereof
when the lock is in its lowermost position,
substantially as specified.
10. In a car-coupler, the combination with
85 the draw-head, of a pivoted knuckle and a sin-
gle-piece lock extending through the draw-
head from top to bottom and provided with a
lock-set shoulder to engage the draw-head
90 and set or support the lock in position for
uncoupling, and a further lock-set shoulder
95 to set or support the lock on the rear arm or
tail of the knuckle in position for coupling,
said lock being also provided on its front side
near its upper end with a shoulder to prevent
creeping of the lock, said draw-head being
100 provided with a flange or shoulder to engage
said shoulder on the lock near the upper end
thereof when the lock is in its lowermost position,
said lock being further provided with a
foot or projection on the rear side thereof
105 to engage the bottom web or floor of the draw-
head and support the lock to the rear side of
its center and cause its upper end to tilt for-
ward when the lock is in its lowermost position,
110 substantially as specified.
11. In a car-coupler, the combination with
115 the draw-head, of a pivoted knuckle and a lock
provided with a lock-set shoulder to engage
the draw-head and set or support the lock in
position for uncoupling, and a further lock-
set shoulder to set or support the lock on the
120 rear arm or tail of the knuckle in position for
coupling, said lock being also provided on its
front side near its upper end with a shoulder
to prevent creeping of the lock, said draw-
head being provided with a flange or shoul-
125 der to engage said shoulder on the lock near
the upper end thereof when the lock is in its
lowermost position, said lock being further
provided with a foot or projection on the rear
side thereof to engage the bottom web or
130 floor of the draw-head and support the lock to
the rear side of its center and cause its upper
end to tilt forward when the lock is in its
lowermost position, and said lock having an

inclined cap or flange at its upper end and the draw-head having an inclined upper face surrounding the lock-opening therein, substantially as specified.

- 5 12. In a car-coupler, the combination with a draw-head, of a pivoted knuckle and a single-piece lock extending through the draw-head from top to the bottom and provided with a lock-set shoulder to engage the draw-head and set or support the lock in position for uncoupling, and a further lock-set shoulder to set or support the lock on the rear arm or tail of the knuckle in position for coupling, said lock being also provided on its front side

near its upper end with a shoulder to prevent 15 creeping of the lock, said draw-head being provided with a flange or shoulder to engage said shoulder on the lock near the upper end thereof when the lock is in its lowermost position, said lock being further provided with an inclined cap or flange at its upper end and the draw-head being provided with an inclined upper face surrounding the lock-opening therein, substantially as specified. 20

GUSTAF A. HERMANSON.
